UNITED STATES PATENT OFFICE.

JAMES W. ARROWSMITH, OF MORRISTOWN, NEW JERSEY, ASSIGNOR TO ARROWSMITH MFG. COMPANY, INC., OF MORRISTOWN, NEW JERSEY, A CORPORATION OF NEW JERSEY.

METATARSAL SUPPORT.

1,358,606.

specification of Letters Patent.

Patented Nov. 9, 1920.

Application filed March 10, 1917, Serial No. 153,844. Renewed September 14, 1920. Serial No. 410,194.

To all whom it may concern:

Be it known that I, JAMES W. ARROWSMITH, a citizen of the United States, and a resident of the city of Morristown, in the county of Morris, State of New Jersey, have invented certain new and useful Improvements in Metatarsal Supports, of which the following is a specification.

The improvements relate to devices for supporting and strengthening and correcting deformities of the bony structure of the human foot, and more particularly to appliances of this kind intended for the purpose of remedying and preventing deformities 10 of the metatarsal and phalangeal section as well as the tarsal.

Heretofore various appliances have been used for the purpose of treating abnormalities of the metatarsal structure, including ordinary instep arch supports with means—adjustable or otherwise—for creating pressure at certain points in this region, flexible insoles with similar provision and metal supports made capable of adjustment at the forward part. These appliances, however, have all proved unsatisfactory in many cases, and it is to overcome the objections to them that the present improvements are designed, as well as to provide a highly efficient and effective support for the entire underarch of the foot both longitudinal and transverse.

The improvements are illustrated in the accompanying drawings, in which Figure 1 is an underside view of a support embodying the improvements; Fig. 2 is a vertical section of the same on the line 2—2 of Fig. 1, looking in the direction indicated by the arrows; Figs. 3 and 4 are side views showing different positions.

The main-plate 1 is of ordinary construction, having an arched bottom portion and an upturned side portion, and extending from the calcaneum to a point in proximity with the anterior metatarsal region.

Forward of this plate is another plate 3 extending from the front edge thereof to a point beyond the metatarsophalangeal joint and arched longitudinally and laterally to approximate the normal arch of the foot skeleton in this zone.

The two plates are secured to a flexible cover 4, extending beyond them on all sides, but are not secured to each other, the cover forming a flexible hinge permitting inde-

pendent vertical movement of the two plates but holding them against lateral or longitudinal displacement.

The forward edge of the main plate 1 extends beyond and underlies the rear edge 60 of the metatarsal plate 3, and the overlapping edges of both plates are formed at an angle to the longitudinal axis of the support, to approximate the angle of the metatarsophalangeal joints. They are also of reduced thickness at their overlapping edges, so that their combined thickness is but little greater than the normal thickness of either plate, and these edges are arched laterally so as to conform to the shape of the foot 70 and coincide in contour as well as width. The main-plate is secured by the rivets 5 and 6, and the metatarsal plate by the rivets 7 and 8 at its forward part and the rivet 9 at its rear edge. This last named rivet holds 75 the rear edge of the plate in close contact with the cover and prevents it from slipping beneath the edge of the main plate when the cover is flexed, so that the wearer cannot accidentally change their relative superposed positions and thus change the character and effect, as hereinafter explained.

The forward edge of the main-plate 1 extends an appreciable distance beyond the rear edge of the metatarsal plate 3, and the 85 said rear edge of the metatarsal plate overlying the forward edge of the main-plate is supported thereon, so that when the main-plate is tilted vertically on its front edge the metatarsal plate is slightly raised. The result of this construction is that the main-plate acts as a lever of the second class, the extreme front edge being the fulcrum, the portion back of the metatarsal plate the power, and the rear edge of the metatarsal 95 plate the weight, and at each step of the wearer the metatarsal plate is slightly raised and lowered.

The construction and action of the plates above described has an important effect on 100 the bony structure and the muscles and ligaments of the metatarsophalangeal section of the foot. With a fixed plate the metatarsal arch is merely supported and held in its proper position, and with this provision the 105 muscles and ligaments in many cases are not exercised and become atrophied, and as weakness or falling of the arch is usually due to a deterioration of these members the defect is not remedied but merely compen-

sated for in a certain degree. With the articulated support of the present improvements, however, these members are flexed and exercised and in many cases restored to their 5 normal condition by such exercise. In addition to this the articulated metatarsal support giving flexibility corresponding approximately to the normal longitudinal flexure greatly increases the comfort and ease 10 of walking. The digital flexors, extensors and interosseous muscles or lumbrales instead of being relieved of their functions are merely relieved of the strain of supporting the arch, which has proved too great for 15 them, and are constantly exercised and developed in a manner tending to strengthen them and restore them to normal condition and tension, by the lever action which has its greatest effect posterior to the distal ends 20 of the metatarsal bones and diminishes in effect toward the digits. In short the articulation of the plates corresponding to the metatarsophalangeal articulation and the construction and arrangement of the two 25 plates result in a relatively perfect fit, a harmonious action and an exercise of the parts tending toward their restoration.

Various modifications of the construction herein described and shown may be made, 30 and the improvements as described may be varied within certain limits so as to secure one or all of the beneficial effects herein described, without departing from the scope of the invention, and it is not intended to 35 limit the subjoined claims to the details of construction herein described and shown, except as otherwise in said claims specified.

What I claim is:

1. A support of the character described, 40 comprising a plate extending under the tarsal and metatarsal zones of the foot and arched to approximate the normal arch of the said parts, a second plate located forward thereof extending to the metatarsophalangeal region, the rear edge of the second plate overlapping the forward edge of the first plate and being arched to approximate the arch of the anterior metatarsus, a 45 piece of flexible material extending over the overlapping portions of the two plates, and a connection between the second plate and said piece back of the forward edge of the first plate.

2. An arch support, comprising in its construction two plates hinged together a line positioned over at the metatarsophalangeal articulation and extending forward and rearward thereof, said plates being arched to approximate the arch of the foot which they 50 underlie.

3. A support of the character described comprising a plate extending under the metatarsal zone of the foot, a second plate located forward thereof, having its rear portion 55 overlapping the forward portion of the

said first named plate, the said two plates being made of relatively rigid sheet material and approximating in width the width of a plurality of the metatarsal bones, and their forward edges adapted to rest upon the sole 70 of a shoe, and a flexible hinged connection between the said two plates permitting relative vertical movement of their adjacent edges.

4. A support of the character described 75 comprising a plate extending under the metatarsal zone of the foot, a second plate located forward thereof, having its rear portion overlapping the forward portion of the said first named plate, the said two plates 80 being made of relatively rigid sheet material and approximating in width the width of a plurality of the metatarsal bones, and their forward edges adapted to rest upon the sole of a shoe, and a flexible hinged connection 85 between the said two plates permitting relative vertical movement of their adjacent edges, said hinged connection comprising a piece of flexible material extending over the said adjacent edges and connected with both 90 plates.

5. A support of the character described, comprising a plate extending under the metatarsal zone of the foot, a second plate located forward of and having its rear portion 95 overlapping the forward portion of the first plate, the said two plates being made of relatively rigid material, and a flexible connection between the said two plates permitting independent movement of the said 100 plates at their overlapping portions, and the construction being such that the said two plates may have upward and different angular movements simultaneously.

6. A support of the character described, 105 comprising a plate extending under the metatarsal zone of the foot, a second plate located forward of and having its rear portion overlapping the forward portion of the first plate, the said two plates being made of 110 relatively rigid material, and a flexible connection between the said two plates permitting independent movement of the said plates at their overlapping portions, and the construction being such that the said two 115 plates may have an upward and angular movement simultaneously, the said two plates having a width greater than the width of a plurality of the metatarsal bones and the second plate having an upwardly arched 120 portion forward of the first plate.

7. A support of the character described, 125 comprising a plate extending under the metatarsal zone of the foot, a second plate located forward of and having its rear portion overlapping the forward portion of the first plate, the said two plates being made of relatively rigid materials, and a flexible connection between the said two plates permitting independent movement of the said 130

plates at their overlapping portions, and the construction being such that the said two plates may have an upward and independent angular movement simultaneously.

- 5 8. A support of the character described, comprising a plate extending under the metatarsal zone of the foot, a second plate located forward of and having its rear portion overlapping the forward portion of the

first plate, the said two plates being made of relatively rigid material, and a flexible connection between the said two plates permitting independent movement of the said plates at their overlapping portions.

Witness my hand this 2nd day of March, 15
1917, at the city of New York, in the county
and State of New York.

JAMES W. ARROWSMITH.
